(57) **CLAIM**

The ornamental design for a tire tread, as shown and described.

DESCRIPTION

FIG. 1 is a perspective view of the tire tread of the present application;

FIG. 2 is an enlarged perspective view of approximately one-quarter portion thereof;

FIG. 3 is an enlarged partial side view of approximately one-quarter portion of the inside thereof;

FIG. 4 is an enlarged partial side view of approximately one-quarter portion of the outside thereof; and,

FIG. 5 is an enlarged partial front view thereof.

The broken line showing of the sidewall, inner bead, and the peripheral boundary between the tire tread and the sidewall is included for the purpose of illustrating environment and forms no part of the claim. The remaining three-quarter portions of the full tire (FIGS. 2-4) are repetitive of the illustrated one-quarter portion.
